(57) **CLAIM**

The ornamental design for a bicycle helmet, as shown and described.

DESCRIPTION

FIG. 1 is a front perspective view of a bicycle helmet showing my new design;

FIG. 2 is a rear perspective view thereof;

FIG. 3 is a front view thereof;

FIG. 4 is a left side view thereof;

FIG. 5 is a right side view thereof;

FIG. 6 is a rear view thereof; and,

FIG. 7 is a top view thereof.

The broken lines shown in the figures depict portions of the bicycle helmet that form no part of the claimed design.
